US0D1106106S

(12) **United States Design Patent** (10) **Patent No.:** **US D1,106,106 S**
(45) **Date of Patent:** **** Dec. 16, 2025**

(54) **ELECTRONIC DEVICE**

(71) Applicant: **Samsung Electronics Co., Ltd.**

Suwon-si (KR)

(72) Inventors: **Sangil Park**, Suwon-si (KR); **Sangsik Park**, Suwon-si (KR)

(73) Assignee: **Samsung Electronics Co., Ltd.**
Suwon-si (KR)

(**) Term: **15 Years**

(21) Appl. No.: **29/937,813**

(22) Filed: **Apr. 17, 2024**

(30) **Foreign Application Priority Data**

Nov. 24, 2023 (KR) 30-2023-0047137

(57) **CLAIM**

The ornamental design for an electronic device, as shown and described.

DESCRIPTION

FIG. 1 is a front perspective view of a electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 1;

FIG. 10 is an enlarged view of the encircled portion 10 in FIG. 1;

FIG. 11 is an enlarged view of the encircled portion 11 in FIG. 1; and,

FIG. 12 is an enlarged view of the encircled portion 12 in FIG. 8.

The evenly-dashed broken lines in the figures depict portions of the electronic device that form no part of the claimed design.

The dot-dash broken lines encircling portions of the claimed design that are illustrated in enlargements form no part of the claimed design.

1 Claim, 12 Drawing Sheets
